SUCTION NOZZLE

Lizzie Linghammar, Skanninge, Sweden, assignor
to Electrolux Corporation, Dover, Del., a corpora-
tion of DelawareApplication May 21, 1936, Serial No. 80,931
In Sweden January 5, 1934

4 Claims. (Cl. 15—155)

My invention relates to vacuum cleaners and more particularly to suction nozzles for vacuum cleaners.

Among the objects of my invention is to provide a nozzle having a mouth piece portion made of soft flexible material, in order that the mouth piece opening may conform closely to any type of surface, whether regular or irregular. Another object of my invention is to provide internal projections within such a mouth piece for preventing closing of the passageway therethrough under the effects of suction or of pressing the nozzle against a surface.

Further objects will be apparent from the following description considered in connection with the accompanying drawing, which forms a part of this specification and of which:

Fig. 1 is a side-view, partially in cross-section, of a preferred embodiment of my invention;

Fig. 2 is a cross-sectional view taken on the lines 2—2 of Fig. 1;

Fig. 3 is a view of the nozzle shown in Fig. 1, but with the walls pressed toward each other;

Fig. 4 is an end view of the nozzle illustrating how it may be deformed to conform to an irregular surface;

Fig. 5 is a view of a nozzle shown in Fig. 1, but applied in reversed direction to a suction conduit;

Fig. 6 is a view of a second embodiment of my invention; and

Fig. 7 is a side view of a third embodiment of my invention.

Referring more particularly to Figs. 1 and 2, reference character 10 designates a hollow suction conduit to one end of which is applied a nozzle in accordance with the present invention, designated generally by reference character 11. Nozzle 11 includes a cylindrical portion 12 which is adapted to receive and engage one end of conduit 10. Secured to cylindrical portion 12 is a conical or funnel-shaped portion 13, which forms the mouth piece of the nozzle. Portion 13 is made of soft flexible material, such as comparatively thin soft rubber. It is usually advantageous to make portions 12 and 13 integral and of the same material, although as far as the present invention is concerned these two portions may consist of separate pieces and only the mouth piece 13 need be of soft material.

The interior of mouth piece 13 is provided with a plurality of inwardly extending ribs 14. These ribs are integral with the mouth piece wall and serve to stiffen the walls sufficiently to prevent its collapse under the effect of suc-

tion, without stiffening it so much as to prevent its desired deformation.

The lower and larger end of portion 13 forms the suction opening of the nozzle and is preferably cut at an angle to the axis of the 5 nozzle. As shown in Fig. 1, this angle is approximately 50 degrees but it may vary within wide limits.

In operation the suction conduit 10 is connected to a vacuum cleaner unit which draws air 10 inwardly through the conduit 10. When the lower open end of the nozzle is applied to a surface, the air moving into the nozzle entrains dust and carries it to the vacuum cleaner unit. The flexible nature of the nozzle mouth piece enables 15 it to conform closely with the surface undergoing cleaning, even though this surface is irregular, and it is possible to vary the area and shape of the inlet opening by changing the pressure of the end of the nozzle against the surface. The low pressure existing within the nozzle mouth piece is prevented from collapsing the mouth piece due to the stiffening ribs 14.

The obliquity of the end of the mouth piece enables it to be held in contact with a horizontal 25 surface while the conduit 10 is inclined, which is the most natural working position. Also, it enables the nozzle to reach into corners.

In the event that the nozzle is pressed angularly against a surface with sufficient force to 30 deform the walls, as shown in Fig. 3, the ribs 14 on one side contact the other side of the mouth piece and thus prevent a complete closure of the passage through the mouth piece.

In Fig. 4 there is illustrated the adaptability 35 of the nozzle to an uneven surface. Reference character 11 designates the nozzle in its normal shape, while reference characters 11a and 11b designate the shape of the nozzle when deformed to conform with the surface. As shown in this 40 figure, the nozzle may be positioned substantially horizontally with the surface and then pressed against it so that the opening in the end of the mouth piece is closely adjacent to the surface. When the nozzle in this condition is 45 moved over the surface, the air rushing into restricted opening carries with it dirt adhering to the surface.

If a small round nozzle opening is desired, as for cleaning the tufts of tufted furniture, the nozzle 11 may be removed from the suction conduit 10, and replaced thereon in reverse position, as is shown in Fig. 5. In order to permit this, it is desirable that the diametral distance between the ribs 14 be no less than the internal diameter of 55

portion 12 of the nozzle. As appears clearly in Fig. 1, the depth of these ribs or the amount they project inwardly decreases toward the smaller end of conical portion 13 in order that the diametral distance between the ribs may be at all places equal to or greater than the internal diameter of portion 12. It will be understood that the internal diameter of the device is of the proper size to receive the suction conduit in either end of 10 the same.

In the nozzle shown in Fig. 6, the edge of the mouth piece bounding the suction internal is serrated, as shown at 15 in order that the nozzle shall not form too perfect a seal with the surface 15 undergoing cleaning. If this surface is smooth, such as a hard wood floor, the resilient nature of the mouth piece might cause it to form such a perfect seal that the resulting internal suction might make it difficult to move the nozzle over 20 the surface. The serrations 15 assure sufficient flow of air to prevent this.

Instead of providing a plurality of straight ribs 14, helical ribs 16 may be provided as is shown in Fig. 7.

25 In each of the embodiments the relation of the dimensions and spacing of the projections or ribs and the flexibility of the material of which the mouthpiece of the nozzle is made is so chosen that even if the walls are pressed together, as 30 shown in Fig. 3, the projections prevent complete closure of the passageway through the nozzle. Consequently, due to this action of the projections, the nozzle may be squeezed, rolled or twisted into a variety of shapes without possibility of cutting off flow of air therethrough. It 35 may even be bent laterally, that is back on itself, in order to reach otherwise inaccessible places, without closing the passage.

While I have described more or less specific embodiments of my invention, it is to be understood 40 that this has been done for purposes of illustration only and that further embodiments and modifications fall within its scope, which is to be limited only by the appended claims viewed in the light of the prior art.

45 What I claim is:—

1. A nozzle for a suction cleaner comprising a tubular body of soft resilient material constructed to receive the end of a suction conduit, said tubular body having one end portion funnel-shaped and provided with ribs extending substantially from end to end of said funnel-shaped portion for reinforcing and preventing complete collapse of the same, said ribs being diametrically spaced in a manner to provide an opening of sufficient size to receive the suction conduit and permit reversal of the nozzle thereon, whereby either end of the tubular body may be used as a cleaning nozzle. 10

2. A nozzle member for a suction cleaner comprising a body at one end constructed to form a 15 socket to receive the end of a suction conduit and having its other end formed of relatively soft resilient material and flared outwardly and provided interiorly thereof with ribs extending substantially throughout its length to reinforce and 20 prevent complete collapse of the nozzle, said ribs being diametrically spaced to provide an opening of a size to receive the end of a suction conduit, whereby either end of the body may be used as a 25 cleaning nozzle.

3. A suction nozzle having a funnel-shaped portion of soft resilient material, and inwardly projecting ribs in said funnel-shaped portion decreasing in the amount they project inwardly toward the smaller end of said portion. 30

4. A nozzle member for a suction cleaner comprising a tubular body having one end constructed as a socket to receive the end of a suction conduit and its opposite end constituting the nozzle portion proper and formed of relatively soft resilient material to facilitate manipulation and deformation thereof, the nozzle portion being gradually flared toward its suction opening and having inwardly projecting ribs extending longitudinally throughout substantially its length to 40 reinforce and prevent complete collapse of said nozzle portion, said ribs decreasing in the amount they project inwardly of the nozzle members toward the socket end of the nozzle member. 45
